UNITED STATES PATENT OFFICE.

ERNEST S. JEFFERIES, OF HAMILTON, ONTARIO, CANADA, ASSIGNOR OF ONE-THIRD
TO EBENEZER A. W. JEFFERIES, OF WORCESTER, MASSACHUSETTS.

APPARATUS FOR ELECTRICALLY HEATING METAL BARS.

Application filed December 19, 1921. Serial No. 523,502.

My invention relates to apparatus for heating metal bars and has for its object to provide an improved apparatus of the class described whereby metal bars, billets, rods, 5 and the like may be quickly and economically heated by the passage of an electric current therethrough, preparatory to the performance of some operation, such as reducing or forming, upon the bars while in a heated condition. Further objects of my 10 invention are to provide an apparatus of the above described type whereby the material can be conveniently handled prior to its being heated, and whereby the heated 15 material may remain in the apparatus with a minimum loss of heat therefrom prior to its removal from the apparatus for the performance of further operations thereon.

These, and other advantageous features of 20 my invention will hereinafter more fully appear, reference being had to the accompanying drawings in which,

Fig. 1 is a view in side elevation of a heating apparatus embodying my invention.

Fig. 2 is a plan view of the apparatus shown in Fig. 1.

Fig. 3 is a view in side elevation showing a portion of the apparatus shown in Fig. 1 on an enlarged scale.

Fig. 4 is a view in end elevation of the parts shown in Fig. 3.

Fig. 5 is a transverse sectional view along the line 5, 5 of Fig. 1, looking in the direction of the arrow.

Fig. 6 is an enlarged view of a portion of the parts of Fig. 3 showing the details of one of the electrodes.

Fig. 7 is a sectional view along the line 7, 7 of Fig. 6.

Like reference characters refer to like parts in the different figures.

Referring to the Figs. 1 and 5 of the drawings, the apparatus generally comprises a frame which consists of spaced longitudinal side members 1 which are supported above the ground or floor by upright members 2 and are tied together by cross members 3. Plates 4 are carried by the side members 1 and the cross members 3 and constitute the bottom of a generally trough-like structure, the sides of which are provided by the vertical flanges 5 of the side members 1.

As best shown in Fig. 5, a layer of blocks or bricks 6 composed of some suitable re-

fractory material, such as fire clay is arranged so as to completely fill the trough described above and to provide a smooth surface generally rectangular in form. A second layer of refractory bricks 7 is then arranged upon the bricks 6, one side of each brick 7, except the right end brick 7^a, being provided with an inclined surface 8. The bricks 7 are spaced apart with the inclined surface 8 of one brick facing the vertical side of the next brick so as to provide a series of open chambers 9, each having an inclined surface on one side thereof and with the bottoms of the chambers formed by the exposed top surfaces 10 of the bricks 6. A third layer of bricks 11 is arranged upon the bricks 7, the underside of each brick 11, except the left hand end brick 11^a, being provided with a beveled surface 12 which overhangs a chamber 9 between the bricks 7. The bricks 11 are spaced apart so as to leave exposed a portion of the top surface of each brick 7 adjacent to the beveled surfaces 8. In this way, chambers 13 are left between the bricks 11 which communicate with the chambers 9 between the bricks 7.

A fourth layer of bricks 14 is arranged upon plates 15 covering the bricks 11 and each brick 14, except the left hand end brick 14^a, is provided with a beveled surface 16 overhanging a chamber 13. The bricks 14 are spaced apart in somewhat the same manner as the bricks 11, thus leaving a portion of each plate 15 exposed, adjacent to the edge of each chamber 13. The chambers 17 thus provided between the bricks 14 communicate with the chamber 13. The side walls of the chambers 17 are covered with plates 18 and the tops of the bricks 14 are covered with plates 19. The bricks 6, 7, 11 and 14, in the several layers, are secured together by means of bolts 20 extending between the side members 1 and the top plates 19.

From the foregoing, it is apparent that when all of the bricks 6, 7, 11 and 14 have been arranged and secured together as described, they provide in effect a rectangular block of refractory material having a series of parallel chambers 9, 13 and 17 extending longitudinally therethrough, each series of chambers being offset with respect to the other series of chambers.

Referring to Figs. 1 and 2, the bricks 6, 7, 11 and 14 are spaced apart at intervals to provide a plurality of continuous slots 21 extending substantially at right angles to, and intercepting the chambers 9, 13 and 17. A plurality of arms 22 are located in each of the slots 21 and are mounted in spaced relation on shafts 23 extending longitudinally of the frame below the side members 1. As best shown in Figs. 1 and 5, each shaft 23 is provided at a point intermediate its ends with a rocker arm 24 that is connected by a rod 25 to one arm 26^a of a bell crank lever 26, all of the levers 26 being mounted in spaced relation on a shaft 27 extending across the frame between one pair of upright members 2. The lower arm 26^a of each lever 26 is connected by a rod 28 to one arm 29^a of a bell crank lever 29. As best shown in Fig. 4, the bell crank levers 29 are mounted in spaced relation on a shaft 30 extending across the frame between a pair of braces 31 supported by the upright members 2. The upper arm 29^b of each lever 29 is provided with a foot treadle 32 by means of which the lever 29 may be operated, as will be hereinafter described.

As best shown in Figs. 1 and 5, a plurality of electrical bus bars 33 are supported below the bottom plates 4 of the frame by means of insulators 34 suspended from the cross members 3. The bus bars 33 are arranged in pairs spaced apart at their ends and the adjacent ends of each pair of bus bars are connected to the terminals of a suitable source of electrical energy, such as a transformer 35, by means of conductors 36.

As best shown in Fig. 3, the outer ends of each pair of bus bars 33 are bent upwardly and extend into a chamber 37 provided in the fire brick structure at the ends of the chamber 9 and 13. The bus bars 33 are preferably formed of separate laminations, so that the portions which are bent upwardly possess a certain amount of inherent resiliency, as will be hereinafter referred to. The upper end of each bus bar 33 terminates in a cap or head 38 which, as best shown in Figs. 6 and 7, is grooved to receive a plate 39. The plate 39, in turn, carries an electrode 40 which is preferably composed of some heat resistant conducting material, such as tungsten or carbon, having a higher melting point than the material which is to be heated in the furnace. Each plate 39, together with its electrode 40, is removable from the head 38 so that an electrode may be readily removed or repaired, as will be hereinafter pointed out.

Each heat 38 is secured between a pair of arms 41 pivotally supported below the chamber 37 on a bracket 42. The brackets 42, at each end of the frame are supported in spaced relation on a cross member 43 formed of some suitable insulating material, such as

wood. A sector 44 is mounted to turn freely on the shaft 45 of each pair of arms 41, and is provided with a plurality of teeth 46. A bar 47, pointed at one end as indicated at 48, is pivotally connected at its other end to one arm 49^a of a bell crank 49, and the pointed end 48 of the bar 47 normally rests in engagement with the teeth 46. The other arm 49^b of the bell crank 49 is connected, by means of an arm 50, to the end of the shaft 23 which carries one set of pusher arms 22. Each shaft 23 is similarly connected at its ends to a pair of bars 47.

One arm 41 of each pair carries a stop plate providing lugs 52 and 53 extending on opposite sides of one side member 54 of the sector 44. The lugs 52 and 53 are provided with set screws 55 and 56 respectively, the member 54 normally resting against the set screw 55. Each head 38 is further connected to the bracket 42 by means of a link 57, the length of the link 57 between its points of pivotal connection being substantially the same as the length of each arm 41 between its points of pivotal connection to the head 38 and to the bracket 42 respectively, for a purpose to be hereinafter described. Each head 38 is further provided with a lug 58 within which is slidable a push-off 59, the lower end of which is connected to the sector 44 by means of a link 60, so that the push-off 59 is movable by the sector 44 parallel to the face of the electrode 40, as will be hereinafter described.

Having thus described the various parts entering into my invention, the operation thereof is as follows:—The bars, billets, or other pieces of material which it is desired to heat, are first cut into lengths which are slightly greater than the lengths of the chambers 9, 13, and 17, and are then placed on top of the plates 15, as indicated at 51 in Fig. 5. The operator or operators, as the case may be, then push a bar into each top chamber 17, so that the several bars will rest on the exposed portions of the plates 15, which, together with the plate 18, protect the bricks 11 and 14 from injury. A bar having been thus seated in each of the chambers 17, the operators then depress each of the bell cranks 29 by means of the foot treadles 32, thereby causing the shafts 23 to be turned in a clockwise direction. The several sets of pusher arms 22 then move in the slots 21 toward the bars 51, one of which is seated in each of the chambers 17. When the arms 22 engage the bars 51, the latter are pushed off of the plates 15 into the chambers 13, but are caught on shoulders 22^a provided on the arms 22 before they reach the exposed portions of the fire bricks 7. In this position the foot treadles 32 are fully depressed, so that the arms 22 are at the end of their movement to the right.

At the same time that the arms 22 are

- 10 moved to shift the bars as described above, the turning of the shafts 23 causes the several bars 47 to be simultaneously moved in the direction of the arms 41. This movement of the bars 47 causes the pointed ends 48 to engage the teeth 46 and thereby turn the sectors 44 in opposite directions. This turning movement is imparted to the several pairs of arms 41 when the members 54 of the 15 sectors 44 engage the set screws 56, thereby moving the heads 38 at the ends of the bus bars away from the open ends of the chambers 13. This movement of the heads 38 allows the bars 51 to enter the chambers 13 20 without engaging the electrodes 40. The operators then release the foot treadles 32 whereupon the heads 38 tend to return to their original position by reason of the inherent resiliency of the bus bars 33, which 25 will always tend to return to their original form. The arms 41 thereupon move toward the ends of the chambers 13 and it is obvious that this movement will cause the shafts 23 to be turned in a counter clockwise direction. 30 The arms 22 will then move to the left in the slots 21 and in so doing will deposit the bars 51, which are seated on the shoulders 22^a, on the exposed portions of the bricks 7 in the chambers 13, the bars being deposited 35 lightly so that the bricks will not be damaged. As this occurs, the electrodes 40 will engage the projecting ends of the bars, so that each bar is firmly held between the electrodes 40 in the chambers 13 by reason of the inherent resiliency of the laminated conductors. When the heads 38 are moved away from or towards the bars, as described 40 above, the electrodes 40 are always maintained in a vertical position by reason of the parallel motion provided by the arms 41 and links 57, consequently the bars will always squarely engage the electrodes 40. 45 As soon as the electrodes 40 engage the ends of the bars 51, electric current will immediately start to flow through the bars 51, inasmuch as each bar completes the circuit between each pair of electrodes 40. The current flow will of course depend upon the voltage of the source of supply and the cross 50 sectional area of the bars, and it is obvious that the voltage can be so regulated as to cause a flow of current of sufficient strength to heat each bar 51 throughout its length, such heating being uniform in character. When the 55 bars 51 have reached the desired degree of heat the operators move another set of bars from the plates 19 into the chamber 17 and again depress the foot treadles 32. When this occurs the arms 22 are moved as before, whereupon the bars 51 in the heating chambers 13 will be engaged by those portions of the arms 22 below the shoulders 22^a, and will be moved to the right until they reach the beveled surfaces 8 of the fire bricks 7. 60 The heated bars will then slide down the 65 surfaces 8 until they reach the surfaces 10 forming the bottoms of the chambers 9, upon which the heated bars will come to rest. As soon as the arms 22 start to move, and before they engage the heated bars, the latter 70 are released from the electrodes 40 by the upward movement of the push-offs 59 which engage the ends of the bars before the sectors engage the set screws 56, thereby breaking the electrical circuit through each set of 75 bus bars before the heads 38 are moved. This prevents the bars from sticking to the electrodes 40 and reduces arcing to a minimum. 80 Just after the heated bars 51 are engaged by the arms 22, below the shoulders 22^a, the cold bars 51 which are located in the chambers 17, will be removed therefrom by the arms 22, as previously described, and will be deposited at the bottoms of the chambers 85 13 upon the return movement of the arms 22, following the release of the foot treadles 32. The above described cycle of operations can be continued as desired and it is apparent that the bars will be successively seated in a 90 cold condition in the chambers 17, then heated in the chambers 13, and finally deposited, in a heated condition, in the chambers 9, from which they may be removed as 95 desired for further operations thereon, such for example as drawing or forming. 100 It is obvious that after a number of bars have been heated in the chambers 13, and after a number of heated bars have been passed through the chambers 9, the walls of the chambers 9 and 13 will become heated to such an extent that there will be no appreciable loss of heat should the bars be allowed to lie in the chambers 9 for any length of time, owing to the fact that these 105 chambers are surrounded by thick layers of fire brick and the only entrance thereto is through the rather tortuous passages provided between the several sets of chambers. Furthermore, the walls of the chambers 13 110 will retain a considerable amount of heat so that the amount of current required for heating the bars will become less and less as the furnace heats up. Furthermore, it is apparent that ample provision is made for 115 protecting the fire brick surfaces of the chambers 17, into which the bars fall by gravity. In the case of the chambers 13 however, the use of protective plates is impracticable, owing to the fact that the bars 120 must be supported by insulating material while passing the current therethrough, but it is obvious that damage to bricks in these chambers will be prevented by the fact that the arms deposit the bars without shock in 125 these chambers on their return movement in the slots 21. 130 The arrangement whereby the ends of the bus bars are distorted from their normal shape, to permit the entrance of the bars

into the chambers 13, insures that the electrodes 40 will make good electrical contact with the ends of the bars when the bus bars are allowed to return to their normal shape, upon release of the foot treadles. Furthermore, the faces of the electrodes 40 are always maintained substantially vertical by reason of the parallel linkage connecting the heads 38 to the brackets 42, thereby insuring that the ends of the bars will squarely engage the electrodes. The bars are prevented from sticking to the electrodes 40 by operation of the push-offs 59, thus reducing arcing and wear on the electrodes to a minimum. Lastly, the mounting of each electrode 40 on a plate 39 that is separately removable from its head 38, permits ready replacement, or repair, of the electrodes and also makes necessary the use of only a small amount of material for each electrode, which is of considerable importance when relatively expensive metal is employed for the electrodes.

While I have shown my invention in its simplest preferred form, it is obvious that it is susceptible of various modifications, and I desire therefore, that only such limitations be imposed on my invention as may come within the scope of the appended claims.

I claim:

1. In apparatus of the class described, the combination with a heater providing a stepped chamber for receiving material, of an electrode located at one end of said chamber and means for moving said electrode toward and away from one end of said material.

2. In apparatus of the class described, the combination with a heater providing an enclosed stepped chamber for receiving material projecting beyond one end of said chamber, of a movable electrode for engaging the projecting end of said material.

3. In apparatus of the class described, the combination with a heater providing an enclosed chamber and relatively movable electrodes located outside of said chamber, of means for moving material into said chamber with its ends between said electrodes.

4. In apparatus of the class described, the combination with a heater providing an enclosed chamber and a movable electrode located outside of said chamber, of means for moving material into said chamber and for simultaneously causing said electrode to engage one end of said material.

5. In apparatus of the class described, the combination with a heater providing an enclosed chamber and relatively movable electrodes located outside of said chamber, of means for moving said electrodes away from each other to permit a piece of material to be received in said chamber in a downward direction.

6. In apparatus of the class described, the combination with a heater providing an enclosed chamber and relatively movable electrodes located at the ends of said chamber, of means for moving said electrodes away from each other to permit a piece of material to be received in said chamber in a downward direction, and further means for causing said electrodes to engage the ends of the material after the latter has been seated in said chamber.

7. In apparatus of the class described, a furnace provided with a stepped heating chamber and yieldable electrodes provided at the ends of said chamber, said electrodes being movable toward and away from each other.

8. In apparatus of the class described, a furnace provided with a stepped heating chamber, inherently resilient electrodes provided at the ends of said chamber and means for causing relative movement of said electrodes.

9. In apparatus of the class described, the combination with a furnace providing an enclosed chamber for receiving material and an electrode movable toward or away from said material, of means for separating said electrode from said material in advance of its movement away from said material.

10. In apparatus of the class described, the combination with a furnace providing an enclosed chamber for receiving material and an electrode movable toward or away from said material, of means movable independently of said electrode for separating said material therefrom.

11. In apparatus of the class described, the combination with a furnace providing an enclosed chamber for supporting a rod and a movable electrode adapted to make contact with the end of said rod, of means for lifting said rod out of contact with said electrode in advance of movement of said electrode away from said material.

12. In apparatus of the class described, the combination with a furnace providing an enclosed chamber for supporting a rod and a movable electrode adapted to make contact with the end of said rod, of means operable independently of said electrode for lifting said rod out of contact therewith.

13. In apparatus of the class described, a conductor having a bent portion terminating in a head pivotally supported on a movable arm and means for maintaining said head in a vertical position when moved by said arm.

14. In an electric heater having a heating chamber for long bars, a heating circuit adapted to be completed by a bar in said chamber and means in said chamber for maintaining the bar in a heated condition upon removal of the bar from the circuit.

15. In an electric heater, a heating cham-

ber for long bars and a heating circuit adapted to be completed by a bar in said chamber, the said chamber being so constructed as to enclose the bar and maintain it in a heated condition following its removal from the heating circuit.

16. In an electric heater, a heating chamber for long bars adapted to support a bar in a number of separated positions, a heating circuit adapted to be completed by a bar in one of its positions in the chamber, and means for removing a heated bar from the heating circuit to a position in said

chamber in which the bar is maintained in a heated condition.

15

17. In an electric heater, a stepped heating chamber for long bars adapted to support a bar in a number of separated positions, one above the other, a heating circuit adapted to be completed by a bar in one of its positions in the chamber, and means for removing a heated bar from the heating circuit, whereupon the bar moves by gravity to a position in said chamber in which the bar is maintained in a heated condition.
